UNITED STATES PATENT OFFICE.

EWALD C. GOEPEL, OF NEWARK, NEW JERSEY.

SATCHEL-FRAME ATTACHMENT.

SPECIFICATION forming part of Letters Patent No. 443,138, dated December 28, 1890.

Application filed September 15, 1890. Serial No. 364,949. (No model.)

To all whom it may concern:

Be it known that I, EWALD C. GOEPEL, a citizen of the United States, residing at Newark, Essex county, New Jersey, have invented 5 certain new and useful Improvements in Attachments for Bags and Satchels, fully described and represented in the following specification and the accompanying drawings, forming a part of the same.

10 The object of this invention is to furnish a means of applying a spring to a bag or satchel frame to open the frame automatically when the catch is released. The spring is mounted upon a pivot secured to a foot-piece 15 which may be riveted to the bag-frame. The spring-wire is wound upon the pivot, and is formed with two projecting ends, which are bent, one of them to pass between the outer plates of the bag-frame and the lugs which 20 form the hinge of the same, and the other is bent over the foot-plate into close contact with such outer plate. By securing the foot-piece inside a bag-frame adjacent to the hinge the opposite ends of the spring press upon the 25 opposite sides of the bag-frame and operate to push them apart when uncaught.

In the drawings, Figure 1 is an edge view of the attachment. Fig. 2 is a plan of the same. Fig. 3 is a section across a bag-frame 30 at the points *g* *h* in Fig. 5, with the inner and outer ends separated. Fig. 4 is a similar section with the frame closed, and Fig. 5 is a plan view of the parts shown in Fig. 3.

The spring is formed of wire, with a coil a 35 and projecting ends *b* *b'*. The coil is sustained by a pivot-pin *f*, fixed upon a foot *d* by ears *c*, and the ends *b* *b'* project at right angles to the pivot-pin.

The parts *g* and *h* of the bag-frame and 40 their hinge-ears *i* are shown in the form now usually preferred in Figs. 3 and 5, with the ears upon the inner plates *n* of the frame, and connected by a rivet *r* independently of the outer plates *p*. By this construction the 45 outer plates cover the hinge externally, so that the hinge-rivet is not at all exposed to view. This construction is a very desirable one; but it wholly prevents the winding of a wire spring around the hinge-rivet, as was 50 formerly done when the rivet-wire was extended through the frame to the outside and

journaled in the outer plates *p* of the frame. By my attachment, however, a coiled spring may be applied with its free ends between the frame-sides *g* and *h*, and in such a relation 55 to the hinge as to be coiled more tightly by the movement of the frame in closing the bag. Thus in Figs. 3 to 5 the foot *d* is shown secured to one of the frame-plates *p* by a rivet *e'*, inserted through a hole *e* in the foot, the 60 pin *f* being held as close to the bag-hinge as is practicable. The ends of the spring-wire are extended against the inner sides of the frame, and the coil is so wound as to be tightened when the ends *b* *b'* are pressed toward 65 one another by the closing of the frame. One end *b* of the wire is necessarily extended past the bag-hinge when the frame is open, as in Figs. 3 and 5, and such end is therefore led from the inner end of the pin *f* so as to pass 70 between the hinge-lugs *i* and the frame-plates *p*. The other end *b'* from the outer end of the coil or pin is bent inward over the foot *d* to lie in the corner of the plates *p* and *n*. Both ends are thus wholly prevented from 75 projecting into the bag or satchel. The end *b* of the wire slides upon the plate *p* as the bag is closed, so that its extremity is shown farther from the bag-hinge in Fig. 4 than in Fig. 3. 80

Two ears *c* are shown upon the foot *d* with the pin *f* secured at both ends in the same; but it is immaterial how the pin is supported on the foot, as its function is to form a fulcrum for the spring when twisted by the motion of its free ends *b* *b'*. The foot *d* and ears *c* are formed to hold the end *b* of the wire just between the lugs *i* and the plates *p*, the foot being offset at *d'* to facilitate the adjustment of the foot in the proper relation to 90 the lug *i*, or, the foot being otherwise set, to locate the end *b* between the lugs *i* and the plate *p* when the foot is riveted upon the frame-plate *n*. 85

I do not claim a wire coil applied directly 95 to a bag-hinge, as that is not new and cannot be used with the kind of bag-hinge shown herein, which is commonly known as the "English club."

What I claim as my invention, and desire 100 to secure by Letters Patent, is—

The combination, with a bag-frame having

the outer frame-plates *p* and the inner frame-
plates *n*, provided with hinge-lugs *i* clear of
the outer plates, of the foot *d* and pin *f*, pro-
vided with the wire coil *a*, having opposite
5 ends *b* *b'*, and the foot secured upon the plate
p, with the end *b* of the wire arranged between
the lugs *i* and the plate *n*, substantially as
shown and described.

In testimony whereof I have hereunto set
my hand in the presence of two subseribing *to*
witnesses.

EWALD C. GOEPEL.
